UNITED STATES PATENT OFFICE.

LEO L. PFEIFER, OF COLUMBUS, OHIO, ASSIGNOR TO THE JOHN W. BROWN MANUFACTURING COMPANY, OF COLUMBUS, OHIO, A CORPORATION OF OHIO.

LAMP.

1,165,120.

Specification of Letters Patent. Patented Dec. 21, 1915.

Application filed June 28, 1915. Serial No. 36,846.

To all whom it may concern:

Be it known that I, LEO L. PFEIFER, a citizen of the United States, residing at Columbus, in the county of Franklin and State of Ohio, have invented certain new and useful Improvements in Lamps, of which the following is a specification.

My invention relates to lamps, particularly of the oil burning type adapted for use 10 in connection with automobiles, serving as headlights for these vehicles. One great difficulty with all oil burning headlights or side lights, as they are sometimes called, has been that the rapid movement of the 15 lamp through the air causes an influx of air through the ventilator openings usually adjacent the top of the lamp, this influx of air usually being so great as to at times cause the blowing out of the flame.

Having this in mind, the main object of 20 my invention resides in the provision of a peculiarly constructed chimney, wherein it is practically impossible to have a greater amount of air enter the combustion chamber 25 forming the lamp than that required to support the necessary combustion.

The preferred embodiment of my invention is shown in the accompanying sheet of 30 drawings, in which similar characters of reference designate corresponding parts, and in which:

Figure 1 is a view in side elevation showing the upper portion of the lamp in vertical section, Fig. 2 is a view in side elevation 35 of the internal chimney structure, and, Fig. 3 is a section taken on line 3—3 of Fig. 2.

In the drawings, there is shown an oil receptacle designated by the reference numeral 1, this oil receptacle being of any preferred type and carrying the conventional type of burner structure 2 at its upper end. This burner structure extends into the combustion chamber of a casing body designated generally by the reference numeral 3. 40 This casing body is formed of an exterior member 4 and an interior member 5, the latter being more or less of a reflector and being somewhat smaller in size than the member 4, thereby providing a space 6 between them. The forward end of the casing body is closed by means of a lens shown at 7, this being the direction at which the rays of light are projected. This casing body is surmounted by a chimney and a ventilator 45 structure, the ventilator structure comprising an external member as is shown at 8, this member being provided with a series of apertures 9 along its lower edge and such as are shown at 10 at its top. This ventilator member 8 seats itself upon an opening 6 formed in the top portion of the casing 4 and in order to maintain this portion 4 and the portion 5 in spaced relation, I have provided a collar member such as is shown at 11, this collar member being also provided 61 with a plurality of apertures 12, whereby air may enter through the apertures 9 and 10, pass through the apertures 12 in the collar 11 and to thereby ultimately reach the burner structure 2 through the passage 6. 70

The products of combustion are permitted to pass upwardly into the chimney shown at 13, this chimney being open at its lower end and is secured to the interior of the reflector member 5, as is shown. Its upper end is 75 provided with a series of openings such as shown at 14 and the entire structure held in assembled relation by means of the cap and screw structure 15, threading itself into the top wall of the chimney as is shown at 16. 80 Particular reference to Fig. 1 will show that the openings 14 in the chimney 13 are designed to register with similar openings 17 formed in the ventilator member 8 and in this manner the air has free passage down 85 through the top of the lamp into the combustion chamber when moving at a comparatively rapid gait. When this movement is sufficiently great, the influx of air at this point will be greater than the draft created 90 by the escaping products of combustion from the burner 2 and it is, therefore likely that the flame will be extinguished. In order to overcome this, I have provided the chimney 13 with a frusto-conical member such as is 95 shown at 18, the restricted end of this frusto-conical member being disposed adjacent the upper open end of the chimney, but slightly beneath its level. As is shown in the drawings, this member 18 is rigidly 100 held in position by means of rivets or any other desired type of fastening such as is shown at 19, this member being held in close relation with the chimney member 13 to prevent the admission of air at this point. It 105 will, therefore, be apparent that the restricted opening of the member 18 forms what may be termed a dead air space 20 and the rapid movement of the lamp through the air will pocket a portion of the 110

air in this space to form a cushion or a pressure medium to prevent the direct admission of air into the casing body itself. The natural tendency, therefore, will be for the air to pass directly through the openings 14 and 17. Also, the upper end of the member 18 is smaller in area than its lower end and consequently the velocity of flow of the air through the lower open end will be considerably less than its flow through the upper end and in this manner the admission of an amount of air sufficient to extinguish the flame in the burner 2, is prevented.

From the foregoing description, taken in connection with the accompanying sheet of drawings, it will be apparent that I have provided a type of lamp wherein the chimney structure is regulated to such an extent that the flame carried by the burner 2 will not be extinguished no matter what the speed of travel of the lamp through the air may be. This is rendered possible by the use of the frusto-conical member 18 whose restricted end is disposed adjacent the top of the chimney as is shown, thereby providing the dead air space indicated at 20.

What I claim, is:

In an oil burning lamp, an oil receptacle,

a casing body attached to said receptacle, a burner structure within said casing and operatively mounted in connection with said receptacle, a ventilator member rising from said casing and formed with a series of openings adjacent its top, a chimney within said ventilator and open at its lower end to be in communication with the interior of said casing, said chimney having a series of openings in its side walls adjacent its top positioned to register with the openings in said ventilator, and a hollow frusto-conical member within said chimney arranged with its restricted opening adjacent the top of the chimney but beneath the level of the openings in said ventilator and chimney, the lower portion of the frusto-conical member closely fitting the base portion of the chimney, thereby forming a dead air space between the chimney and the frusto-conical member.

In testimony whereof I affix my signature in presence of two witnesses.

LEO L. PFEIFER.
